UNITED STATES PATENT OFFICE.

CHARLES J. KYLE AND JOHN OUSKY, OF COAL BLUFF, INDIANA.

RAIL-ANCHOR.

1,178,324.

Specification of Letters Patent.

Patented Apr. 4, 1916.

Application filed October 4, 1915. Serial No. 54,018.

To all whom it may concern:

Be it known that we, CHARLES J. KYLE and JOHN OUSKY, citizens of the United States, residing at Coal Bluff, in the county of Vigo and State of Indiana, have invented certain new and useful Improvements in Rail-Anchors; and we do declare the following to be a full, clear, and exact description of the invention, such as will enable others skilled in the art to which it appertains to make and use the same.

This invention relates to rail anchors or anti-creeping devices.

The object of the invention is to provide a simply constructed and efficient device of this character which may be readily applied to a rail by an unskilled workman and when applied the gripping effect thereof will be increased by the pressure exerted thereon by the tie against which the device abuts, thereby securely locking the rail without lessening the action of the spiking of the rail to the tie to assist in this function.

With this and other objects in view the invention resides in certain novel features of construction, combination and arrangements of parts to be hereinafter more fully described and claimed.

In the accompanying drawings: Figure 1 represents a plan view of a portion of a rail and a tie showing a pair of these improved anchors applied to the rail on opposite sides of the tie; Fig. 2 is a transverse section taken on the line 2—2 of Fig. 1; Fig. 3 is a detail perspective view of one of the anchors with the locking wedge removed; Fig. 4 is a similar view of the locking wedge.

The anchor constituting this invention comprises a casting formed of a body portion 1 arranged to lie under the base of a rail as is shown clearly in Figs. 1 and 2. Formed integral with the body portion 1 is a clip 2 conformed and adapted to embrace one edge of the base of the rail R with which the anchor is associated. The upper face of the body portion 1 of this anchor has a step-shaped seat formed therein, the upper step 3 of which is designed to receive the base of the rail R, one edge of which extends under and is engaged by the clip 2, and the other edge thereof projects beyond the edge of the seat 3 and is designed to be engaged by a locking wedge 5 adapted to be slidably engaged with the seat 4 formed by the lower step of the anchor seat above referred to. The outer side wall of the seat 4 is undercut

as shown at 6 and is inclined toward one side of the body 1 to receive the tapered wedge 5, one wall only of which is inclined to fit within the seat 4 and engage the inclined undercut wall 6 thereof. The opposed wall of this wedge 5 has a longitudinally extending groove 7 adapted to engage and shaped to conform to the overhanging edge of the rail base which projects beyond the free or inner edge of the seat 3, (see Fig. 2). This wedge 5 is adapted to be driven upon the edge of the rail flange opposite the edge embraced by the clip 2 and the upper wall of the groove 7 is extended laterally to form a projecting flange 8 designed to fit over and engage the upper face of one flange of the rail base, its edge being positioned against the rail web, as is shown clearly in Fig. 2.

When the several parts of this improved rail anchor are in the positions illustrated in Figs. 1 and 2, with the grooved wedge 5 tightly fitted upon the base of the rail R, the wedge will travel with the rail in case of creeping, and so automatically lock the parts together, which is accomplished by means of a toe 10 formed on the laterally extending arm 9 cast integral with the body 1, and which extends from the end thereof having the undercut wall 6, as is shown clearly in Fig. 3. This laterally extending arm 9 is preferably reduced in thickness from its inner toward its free outer end and said end is rounded to produce the toe 10, the side of which is adapted to abut against one side of the tie 7, and when pressure is exerted on said toe by the lateral movement of the tie, the gripping action of the anchor will be increased, owing to the biting engagement of one end of the wedge 5 with the rail flange with which it is engaged, and of one end of the clip 2 with the opposite rail flange at a point diagonally opposite to that which is engaged by the wedge 5. This arm 9 is inclined downwardly toward its free end so that the toe 10 on said free end will be positioned to engage the side edge of the tie at a point some distance below the top of the tie to prevent all possibility of said toe becoming disengaged from the tie and slipping over the top thereof, such as might be likely to occur if it were not inclined downwardly to position it in a plane below the body of the anchor. When the wedge 5 is driven into engagement with the rail base, it will assume the position shown in Fig. 2, owing to the configuration of the overhanging

flange 8 and its engagement with the flange of the rail base.

As shown, two of these anchors are provided for each tie arranged on opposite sides 5 thereof as shown in Fig. 1, and these anchors are shown made right and left to adapt them to properly engage and abut the opposite edges of the tie, but it is to be understood that one or more may be employed as de- 10 sired or found necessary. After the toes of these anchors are engaged with the sides of the tie upon which the rail is mounted, creeping of the rail will be prevented.

The several parts of this rail anchor are 15 preferably constructed of malleable iron, although not necessarily so, but the wedge 5 should be formed of some material capable of being slightly distended without danger of breakage when the wedge is forced upon 20 the edge of the rail base, and the wedge should be capable of maintaining its grip upon the rail base after it has been driven into operative position.

This improved rail anchor as above de- 25 scribed, is particularly advantageous inasmuch as expansion or contraction of the several parts, due to the changes in temperature, does not impair the reliability of the anchor as the parts tighten up into locking 30 position when creeping takes place, even though they may have expanded or contracted somewhat, due to the changes in temperature.

We claim as our invention:—
35 A rail anchor comprising a body portion having step-like seats formed in its upper

face, an integral clip overhanging the upper seat, the lower side of the former adapted to engage the upper face of one side of a rail base and the free end of said clip adapted to engage one side of the web of the rail, the lower seat having an undercut outer wall tapering toward one end, the inner wall of said lower seat being adapted to underlie the other side of said rail base, an arm integral 45 with the outer wall of the lower seat and projecting longitudinally of said body portion, said arm being inclined laterally and downwardly and reduced in thickness from its inner toward its outer end, the latter being rounded to form a tie engaging toe, a wedge having its outer edge tapered to fit the undercut wall of the lower seat of said body portion and its inner edge grooved to conform to and engage the outer edge of the 55 last mentioned side of said rail base, and a flange projecting laterally from the inner edge of said wedge, the lower side of the former being adapted to engage the upper face of the last mentioned side of said rail 60 base and the free end of said flange engaging the other side of the web of the rail, substantially as and for the purpose set forth.

In testimony whereof we have hereunto set our hands in presence of two subscribing 65 witnesses.

CHARLES J. KYLE.
JOHN OUSKY.
